UNITED STATES PATENT OFFICE

JULIEN BERGÉ, OF TIRLEMONT, BELGIUM, ASSIGNOR TO RAFFINERIE TIRLEMONTOISE
SOCIÉTÉ ANONYME, OF TIRLEMONT, BELGIUM, A CORPORATION

PROCESS FOR THE PRELIMINARY TREATMENT OF RAW SUGAR, AFTER PRODUCTS OR
THE LIKE BEFORE REFINING

No Drawing. Application filed February 11, 1927, Serial No. 167,597, and in Germany August 26, 1926.

The raw-sugar, after-products or the like, to be cured in the refinery is usually submitted at the beginning of this treatment to a preliminary refining process (affinage) which liberates the sugar crystals from the adhering syrup without consideration of the changes which these sugars experience during the storage. The syrup is obtained in a condition which requires a repeated treatment. 10 By the surface attraction method the sugar introduced, mixed with a syrup of similar composition to that of the syrup adhering to the crystals, is then exposed to centrifugal action, and for the complete purification of 15 the crystals in the centrifuge is covered with water.

The syrup adhering to the crystals of the introduced sugar contains the whole or almost the whole of the non-sugar components of the raw sugar or of the after-products. This has the drawback that, since this syrup in the method described must be further treated, most of these non-sugar contents reach the refinery process.

25 It is known that the syrup present around the crystals of the sugar introduced is of different purity and such that this purity is exposed to changes during the storage of the sugar. During the cooling of the sugar, the 30 purity is reduced by the crystallizing out of the sugar from the syrup, likewise if the water of the syrup is slowly evaporated. If, on the other hand, the sugar is stored in moist chambers, the absorption of water by the 35 syrup raises the purity of the syrup.

These facts are of considerable importance for the further treatment of the sugar in refineries. If by a suitable storage of the sugar, the purity of the syrup adhering to 40 the crystals is so far lessened that further treatment of the syrup is unnecessary, and, if this syrup is then driven from the crystals as far as possible by centrifugal force, only sugar which is almost free from non-sugar 45 contents passes into the refinery; almost the

whole of the non-sugar matter is excluded with the syrup from the further treatment.

According to the invention, this result is obtained by treatment of the sugar during the storage and by the employment of centrifuges with particularly high centrifugal force. The sugars are stored in chambers in which by devices, which may be automatic, the air is brought to a condition of moisture and to a temperature, which allows the sugar to be cooled and simultaneously freed from its moisture. The syrup surrounding the crystals may thus be brought to the lowest purity and should maintain its desugared state up to its further treatment.

At the commencement of the further treatment, the sugar is first freed by centrifuges of particularly high centrifugal force from the largest portion of the adhering syrup. The means for removing the last residue of the syrup, if this should still be necessary, is extremely facilitated by this preliminary treatment, since the sugar treated in this manner can be allowed to settle in contact with a syrup of higher purity and, consequently, need only a very small quantity of covering water for the perfect purification of the crystals by washing, whereby the maximum yield in pure crystals is obtained from the introduced sugar.

Reference is made to applicant's copending application, Serial No. 167,598, filed concurrently herewith, which has resulted in Patent No. 1,775,385, September 9, 1930, and in which particularly high centrifugal forces are discussed in detail.

I claim:

1. The process of reducing the sugar content of syrup adhering to sugar crystals in raw sugars, after-products, comprising placing the said sugar in a storage chamber, and regulating the temperature and moisture content of the air in said chamber to reduce the sugar content of the syrup by crystallization, and then freeing the sugar

from the largest portion of the adhering syrup in a centrifuge exerting a particularly high centrifugal force.

2. The process of reducing the sugar content of syrup adhering to sugar crystals in raw sugars, and after-products, comprising placing the said sugar in a storage chamber, and reducing the temperature and moisture content of the air in said chamber to reduce the sugar content of the syrup by crystallization, and then freeing the sugar from the largest portion of the adhering syrup in a centrifuge exerting a particularly high centrifugal force.
- 15 3. The process of reducing the sugar content of syrup adhering to sugar crystals in raw sugars, and after-products, comprising placing the said sugar in a storage chamber, and regulating the temperature and moisture content of the air in said chamber to reduce the sugar content of the syrup by crystallization to substantially the point of lowest purity, and then freeing the sugar from the largest portion of the adhering syrup.
- 25 4. The process of reducing the sugar content of syrup adhering to sugar crystals in raw sugars, and after-products, comprising placing said sugar in a storage chamber, and reducing the temperature and moisture content of the air in said chamber to reduce the sugar content of the syrup by crystallization to substantially the point of lowest purity, and then freeing the sugar from the largest portion of the adhering syrup.
- 35 5. In testimony whereof I have affixed my signature.

JULIEN BERGÉ.
